MOVABLE CONDUCTOR SUPPORT

Norman J. Peters, Fond du Lac, Wis., assignor
to Damrow Brothers Company, Fond du Lac,
Wis., a corporation of Wisconsin

Application December 2, 1938, Serial No. 243,514

1 Claim. (Cl. 191—12)

The invention relates to apparatus for supporting the supply conductor of a reciprocating electric motor.

The object of the invention is to provide a simple and effective arrangement for carrying an extensible electric cord for supplying current to a reciprocating electric motor. More particularly, the present invention provides a simple and effective arrangement for carrying a cord in the form of a series of loops slideable along a fixed support from a contracted to an extended position.

The invention further consists in the several features hereinafter set forth and more particularly defined by claim at the conclusion hereof.

In the drawings:

Fig. 1 is a plan view of the device embodying the invention, parts of the apparatus being broken away and the cord being shown in extended position;

Fig. 2 is a side elevation view of the device embodying the invention, the cord being shown in contracted position;

Fig. 3 is a detailed perspective view of a part of the cord support.

In the drawings, the numeral 5 designates an electric motor which is mounted on a carriage 6 provided with wheels 7 running in channel guides or rails 8. The carriage 6 may be reciprocated or moved back and forth along the rails 8 by means driven from the motor 5, and in the present instance I have used the drive mechanism more particularly shown in detail in the prior U. S. Patent No. 2,111,247, to Victor Malueg, dated March 15, 1938, wherein the motor 5 has its drive shaft connected by a pulley 9 and belt 10 with a pulley 11 on a shaft 12 which is connected through suitable mechanism (not shown) with a shaft having a pair of drums 13 mounted thereon and adapted to be selectively clutched thereto, each drum having a cord 14 secured thereto at one end and anchored at its other end to one end of the track frame 15. Thus when one of the drums is driven, one of the cords is wound up and the carriage is pulled in one direction along the track, and then when the other drum is driven, the other cord is wound up and the carriage is pulled in the opposite direction along the track.

The motor 5 runs continuously, and the direction of travel of the carriage is reversed through mechanism controlling the reversal of the clutches as more particularly shown and described in said patent. It is to be noted that in the present instance the shaft 16 for the drums

13 has an agitator 17 mounted thereon which is always rotated in the same direction and is arranged to work in a tank 18. The motor is fed with current from a source of supply through a flexible cord conductor 19, one end of which is shown associated with a current control switch 17 and the other with the terminals of the motor. This cord 19 is long enough so that in one position of the carriage, said cord may be arranged in several coils 21. Each of the coils 21 is supported from a fixed support or rod 22 by a bendable metal member 23 which is provided with a tubular portion 24 slidably mounted on the rod 22 and a split tubular portion 25 in which the conductor 19 is mounted. The sides of the tubular portion 25 may be spread or bent out to receive the conductor 19 and then bent back to closed position. The portion 25 is disposed at a slight angle to the part 24 so as to start the coiling of the conductor in the proper direction.

With the above arrangement when the carriage 6 is at one end of the frame 15, the members 23 are arranged in abutting relation and the loops or coils 21 are in their full open position. Then as the motor 5 moves the carriage 6 to the other end of the frame, the coils or loops 21 are pulled out to a straightened position as shown by the full line position in Fig. 1, the members 23 sliding along the support 22 at the same time and spreading out relative to each other. Thus by the movement of the members 23 and the distention and contracting of the loops 21 the cord is paid out or drawn in to accommodate the reciprocation of the carriage 6.

I desire it to be understood that this invention is not to be limited to any particular form or arrangement of parts except in so far as such limitations are included in the claim.

What I claim as my invention is:

In a device having a reciprocating carriage and an electric motor mounted on said carriage for moving the same, means for furnishing current to said motor comprising a flexible cord conductor connected at one end to said motor and having its other end fixed, a rod extending parallel to the path of movement of said carriage, a plurality of carriers, each of said carriers having a tubular portion slidably mounted on said rod and a tubular split portion disposed at an angle to said first named portion and receiving and clamping a portion of said conductor to said carrier, said conductor being looped between adjoining carriers.
